UNITED STATES PATENT OFFICE

WILLIAM A. EDWARDS, OF CHICAGO, ILLINOIS

FUEL MIXER

Original application filed September 20, 1924, Serial No. 738,773. Divided and this application filed December 3, 1926. Serial No. 152,368.

This application is a division of my application Serial No. 738,773, filed Sept. 20, 1924.

The purpose of this invention is to provide in a fuel mixture forming and feeding device for internal combustion engines an improved construction for automatically varying the fuel mixture in accordance with the variation of engine requirements in the idling and with closed or approximately closed 10 throttle and running with open throttle at high speed and under load. It consists in the elements and features of construction shown and described as indicated in the claims.

15 In the drawings:—

Figure 1 is a diagrammatic view of a motor vehicle having its engine equipped with a device embodying this invention.

Figure 2 is a section at the line 2—2 on Figure 1, being axial with respect to the fuel mixture conduit which leads to the engine intake.

Figure 3 is a section at the line 3—3 on Figure 2.

In the drawings the engine intake is indicated at the intake manifold, 1. 2 represents the main fuel supply tank at the rear of the vehicle and at low level with respect to the engine intake. 3 is the fuel duct leading from the main tank to the float bowl or constant 25 level chamber, 4, of the fuel mixture forming apparatus of the general character of a carburetor. 5 is the fuel mixture conduit extending between the float bowl, 4, and the intake manifold. The customary parts for 30 vaporizing the primary mixture and affording additional air supply and for throttle control are conventionally shown, requiring no description for the purpose of the present invention.

35 The part of the construction in which the characteristic of the present invention is contained is a Venturi construction in the fuel mixture conduit which is shown at A closely adjacent to the float bowl, 4, and therefore, 40 in the construction as indicated in the diagrammatic view of Figure 1, at a low level with respect to the engine intake. This Venturi device comprises a greater venturi, 7, having air inlet at 7^a and constriction at 7^b. 45 In this greater venturi there is located and

55 formed a lesser venturi, 8, which is paraxial with the greater venturi, but eccentric with respect thereto, the proximate walls of the two venturis merging in each other. The constriction of the lesser venturi is anterior, along the air path through the two venturis, to the constriction of the greater venturi. The terminal of the fuel duct is formed on a nozzle, 10, for which a bore is made through the adjacent and combined walls of the two 60 venturis approximately at the transverse plane of the constriction of the lesser venturi, said nozzle having a lateral orifice, 10^a, for fuel delivery into the lesser venturi and having its delivery into the greater venturi at 65 an orifice, 10^b, at its extremity, said extremity being positioned substantially in the axis of the greater venturi.

70 The operation of this construction is that under idling conditions, the depression at the constriction of the lesser venturi is adequate to supply a limited quantity of relatively rich mixture through said lesser venturi, which mixes with additional air drawn in through the greater venturi around the discharge mouth of the lesser, and the depression at the terminal orifice of the nozzle becomes so much less than at the constriction of the lesser venturi that air is drawn in through the terminal orifice assisting in atomizing or 75 dispersing the liquid in the initial mixture delivery from the discharge of the lesser venturi. With still wider opening of the throttle and increase of engine speed, the depression at the constriction of the lesser venturi increases, causing increase of fuel drawn, but greater increase of air drawn through both the venturis and up to a certain point, increase of air drawn in through the terminal orifice, 10^b, for dispersing and atomizing the 80 oil at its delivery from the lesser venturi. But as the air velocity and consequent depression at the constriction of the lesser venturi diminishes the increased depression in the greater venturi at the terminal orifice, 10^b, of the nozzle causes the pressure at that point to approach that at the orifice, 10^a, at the constriction of the lesser venturi, and air intake through the terminal orifice, 10^b, of the nozzle eventually ceases; and upon fur- 85 90 95 100

ther increase of air speed, air friction preventing corresponding increase of depression in the lesser venturi, the depression at the orifice, 10^a , eventually equals the depression at the orifice, 10^b , and liquid fuel is delivered to both orifices. Otherwise stated,— upon further increase of the throttle opening causing increase of air speed and consequently of depression in the lesser venturi, said depression being less than that in the greater venturi, the relative depressions become such that liquid fuel is discharged from the terminal orifice, 10^b , so that as stated, liquid fuel will flow out of both orifices, 10^a and 10^b .

15 I claim:—

1. In a fuel mixture feeding apparatus, a fuel mixture conduit comprising a greater Venturi passage and a lesser Venturi passage, the lesser passage being positioned wholly within the greater and having its discharge mouth located proximate the plane of maximum depression of said greater venturi; a continuous fuel supply duct extending for discharge into the lesser venturi substantially at the zone of greatest constriction of said lesser venturi and continued therebeyond for discharge in the greater venturi at a zone of the latter of substantially less than maximum depression.

30 2. In a fuel mixture feeding apparatus, a fuel mixture conduit comprising a greater Venturi passage and a lesser Venturi passage, the lesser passage being positioned wholly within the greater and having its discharge mouth located proximate the plane of maximum depression of said greater venturi; a continuous fuel supply duct extending for discharge into the lesser venturi substantially at the zone of greatest constriction of said lesser venturi and continued therebeyond for discharge in the greater venturi at a zone of the latter a substantial distance anterior to the zone of maximum constriction thereof.

35 3. In a fuel mixture feeding apparatus, a fuel mixture conduit comprising a greater Venturi passage and a lesser Venturi passage, the lesser passage being positioned wholly within the greater and having its discharge mouth located proximate the plane of maximum depression of said greater venturi; a continuous fuel supply duct extending for discharge into the lesser venturi substantially at the zone of greatest constriction of said lesser venturi and continued therebeyond for discharge in the greater venturi at a point relatively distant from the inner surface and proximate the axis thereof.

40 4. In a fuel mixture feeding apparatus, a fuel mixture conduit comprising a greater Venturi passage and a lesser Venturi passage, the lesser passage being positioned wholly within the greater and having its discharge mouth located proximate the plane of maximum depression of said greater venturi; a continuous fuel supply duct extending for

discharge into the lesser venturi substantially at the zone of greatest constriction of said lesser venturi and continued therebeyond for discharge in the greater venturi at a zone of the latter at which the depression is substantially less than the maximum and at a point relatively distant from the inner surface and proximate to the axis of said greater venturi.

45 5. In a fuel mixture feeding apparatus, a fuel mixture conduit comprising a greater Venturi passage and a lesser Venturi passage, the lesser passage being positioned wholly within the greater and having its discharge mouth located proximate the plane of maximum depression of said greater venturi; a continuous fuel supply duct extending for discharge into the lesser venturi substantially at the zone of greatest constriction of said lesser venturi and continued therebeyond for discharge in the greater venturi proximate to the axis of the latter at a zone thereof which is at a substantial distance anterior to the zone of greatest constriction and to the zone of greatest depression, the lesser venturi being positioned eccentrically within the greater and being diametered for leaving the greater venturi unobstructed by the lesser at a longitudinal path proximate the axis of the greater venturi, for permitting the last mentioned fuel discharge proximate said axis.

50 6. In a fuel mixture feeding apparatus, a fuel mixture conduit comprising a greater Venturi passage and a lesser Venturi passage, the lesser passage being positioned wholly within the greater and having its discharge mouth located proximate the plane of maximum depression of said greater venturi; a continuous fuel supply duct extending for discharge into the lesser venturi substantially at the zone of greatest constriction of said lesser venturi and continuous therebeyond for discharge in the greater venturi at a zone of the latter of substantially less than maximum depression and a substantial distance anterior to the zone of maximum constriction thereof.

55 In testimony whereof, I have hereunto set my hand at Chicago, Illinois, this 30th day of November, 1926.

WILLIAM A. EDWARDS.
